UNITED STATES PATENT OFFICE.

JAMES D. FADDEN, OF AUBURN, MAINE, ASSIGNOR TO HIMSELF, AND WILLIAM J. MAHANEY, OF LEWISTON, MAINE.

COLLAPSIBLE LAST.

1,071,901.

Specification of Letters Patent.

Patented Sept. 2, 1913.

Application filed December 7, 1911. Serial No. 664,429.

To all whom it may concern:

Be it known that I, JAMES D. FADDEN, a citizen of the United States, residing at Auburn, county of Androscoggin, State of 5 Maine, have invented certain new and useful Improvements in Collapsible Lasts, of which the following is a specification.

This invention relates to lasts, and particularly to a divided or collapsible last for 10 shoes. In this type of device it is particularly desired to secure a last which, while rigid and firm when in position, shall be capable of collapsing to a sufficient degree to allow it to be easily withdrawn from the 15 shoe.

To the end, therefore, of providing a structure which shall be rigid when in normal position and yet which will collapse to a very considerable degree, and at the same 20 time to afford a structure which shall be simple and economical to manufacture, I have devised my present invention.

The construction and operation of my device will be more fully set forth in the specification which follows and as illustrative of 25 my invention I have shown in the drawings a form and embodiment of device which I find well adapted to practical use.

Throughout specification and drawings 30 like reference numerals are employed to indicate corresponding parts, and in the drawings: Figure 1 is a view of the last in normal position with the interior parts indicated in dotted lines. Fig. 2 is a similar view showing the last in collapsible position, and Fig. 3 is an enlarged view of the link.

I provide a last comprising a heel part 1, a fore part 2 and an instep block 3. These parts are separated by cuts which give to 35 the heel part a line of cleavage back of the waist line. It leaves on the rear of the toe part a projecting angle formed by the surface 4 which is inclined slightly forward and a rearwardly extending intersecting 40 surface 5. The heel part 1 has a face 6 corresponding to the lower portion of the face 4 of the toe part 2, and intersecting this a long inclined face 7 which corresponds with a face 8 on the instep block 3.

On the lower or forward end of the instep block 3 are provided intersecting faces 9 and 10. These form a notch or angular recess which correspond with the face 5 and the upper part of the face 4 of the toe mem- 45 ber 2.

The heel member 1 and the toe member 2 are hinged by a hinge strip 11 pivoted at 12 and 13, working in slots so as to allow the toe member 2 to be swung up relatively to the heel member 1. Above the intersection of the faces 7 and 4 the heel member 1 and the toe member 2 are connected by a link 14 which is pivoted to the toe member 2 at 15 and is slotted at 17 to receive a pin 16 allowing the necessary play in the elevation of the heel section. The slot 17 has a projecting point 17' which affords a retard and frictional grip as the last is brought into extended condition. The instep piece 3 is pinned to the link 14 at 70 either the point 18 or 19, or both of these points, as may be desired. The opening for the upper pin is slightly elongated as indicated at 19' to permit play.

The usual jack hole or socket 20 is provided for supporting the shoe and lasting. The parts are held back by the plunger 21 which is held out by the spring 22. It will be seen that with the last in the position shown in Fig. 1, which is the normal position of the last when in the shoe, the parts 1, 2 and 3 fit snugly together; interlocking in a firm and rigid structure, and held by the end of the plunger 21. If the last be bent by raising the heel or the toe after 75 first depressing the plunger 21 the block 3 is slid up, permitting the point between the intersecting surfaces 5 and 4 to approach the surface 7, thus shortening the last longitudinally and permitting the heel 80 to be withdrawn from the shoe.

The link 14 bears at its upper end against a spring 24, set in a recess in the heel part 1. The tendency of this spring is therefore to keep the parts closed in normal position as 85 shown in Fig. 1 in conjunction with the frictional contact of the point 17' with the pin 16 which also tends to keep the last extended when in normal position.

My invention is not only serviceable as a 100 last but is readily adaptable as an artificial foot.

Various modifications may be made in the construction and operation of my device if within the limits of the appended 105 claims, all without departing from the spirit of my invention.

What I therefore claim and desire to secure by Letters Patent is:

1. An interlocking divided last comprising 110

ing a fore part, a heel part operatively connected thereto for vertical movement relative thereto, and an instep block slidably mounted on said heel part, a connection between the heel part and the instep block whereby a sliding movement is given to the instep block upon the vertical movement of the heel part, said instep block and said fore part having their adjacent faces formed with transverse engaging entrant and re-entrant angles disposed to interlock upon the normal positioning of the parts and to be dislodged upon the collapsing of the last.

2. An interlocking divided last comprising a fore part, a heel part operatively connected thereto for vertical movement relative thereto, and an instep block slidably mounted on said heel part, a connection between said heel part and the instep block and said fore part, whereby a sliding movement is given to the instep block relative to said heel part upon the vertical movement of the heel part, and which movement of

the instep block is vertical relative to said fore part, said instep block and said fore part having their adjacent faces formed with transverse engaging entrant and re-entrant angles disposed to interlock upon the normal positioning of the parts and to be dislodged upon the collapsing of the last.

3. A sectional last comprising a toe, a heel and an instep section, a pivotal connection for said toe and heel sections and a second connection joining all of said sections, said second connection pivotally secured in said toe and instep sections and slidably secured in said heel section, whereby a sliding movement is secured for the instep section relative to the heel section.

In testimony whereof I affix my signature in presence of two witnesses.

JAMES D. FADDEN.
